US00D834372S

(12) **United States Design Patent** (10) **Patent No.:** **US D834,372 S**
(45) **Date of Patent:** **** Nov. 27, 2018**

(54) **ULTRA BASE**

(71) Applicant: **Jackel International, Ltd.**,
Cramlington, Northumberland (GB)

(72) Inventor: **Nicholas Cudworth**, Cramlington (GB)

(73) Assignee: **Jackel International Limited**,
Cramlington Northumberland (GB)

(**) Term: **15 Years**

(21) Appl. No.: **29/587,415**

(22) Filed: **Dec. 13, 2016**

(30) **Foreign Application Priority Data**

Jun. 14, 2016 (EM) 3190065-0003
Jun. 14, 2016 (EM) 3190065-0004

(51) **LOC (11) Cl.** **07-01**

(52) **U.S. Cl.**

USPC **D7/509**

(58) **Field of Classification Search**

USPC D7/509, 500, 523, 522
CPC A47G 19/22; A47G 19/2222; A45F 3/16;

(57) **CLAIM**

The ornamental design for an ultra base, as shown and described.

DESCRIPTION

FIG. 1 is a front perspective view of a first embodiment of an ultra base showing my new design;

FIG. 2 is a front elevational view thereof;

FIG. 3 is a rear elevational view thereof;

FIG. 4 is a right side elevational view thereof;

FIG. 5 is a left side elevational view thereof;

FIG. 6 is top plan view thereof;

FIG. 7 is a bottom plan view thereof;

FIG. 8 is a front perspective view of a second embodiment of the ultra base;

FIG. 9 is a front elevational view thereof;

FIG. 10 is a rear elevational view thereof;

FIG. 11 is a right side elevational view thereof;

FIG. 12 is a left side elevational view;

FIG. 13 is top plan view thereof; and,

FIG. 14 is a bottom plan view thereof.

1 Claim, 14 Drawing Sheets
